UNITED STATES PATENT OFFICE.

DAVID S. ROBERTS, OF BOSTON, MASSACHUSETTS.

OIL-FEEDER.

SPECIFICATION forming part of Letters Patent No. 272,980, dated February 27, 1883.

Application filed January 2, 1883. (No model.)

To all whom it may concern:

Be it known that I, DAVID SANDS ROBERTS, of Boston, in the county of Suffolk, of the Commonwealth of Massachusetts, have invented a new and useful Improvement in Oil-Feeders; and I do hereby declare the same to be described in the following specification and represented in the accompanying drawings, of which—

10 Figure 1 is a front elevation, and Fig. 2 a vertical and transverse section, of an oil-feeder containing my invention, the nature of which is defined in the claims hereinafter presented.

15 In such drawings, A denotes the body or oil-reservoir of the feeder, it being provided at its mouth with a cap or cover, B, screwed therein. From the central part of said cap an eduction-tube, C, extends upward, and at 20 a short distance above the cap has cut upon it a screw, a, upon which is screwed an auxiliary cap, D, which is open at its lower end, and thus, when screwed down, fits closely upon the top of the main cap or cover B. There 25 is within the chamber b of the auxiliary cap a vertical flange, e, that projects above the main cap B and surrounds the tube C concentrically. From the space within the said flange a tube, E, extends down within the oil-reservoir A 30 nearly to its bottom, and there is fixed in the cap D another and shorter tube, F, that opens out of the top of the cap and terminates near the bottom of it and within the space inclosed by the flange e. There is also in the top of the cap D a cup or concavity, d, which surrounds the eduction-tube C.

35 From the above it will be seen that on inverting the oiler for the purpose of discharging oil from its tube C air will pass freely 40 through the tube F, and thence through the tube E, in order to enable oil to escape from the reservoir; also, that should, in the meantime, any oil flow from the reservoir into and through the tube E, such oil will be intercepted by the chamber b, from which it cannot escape by reason of the tube F. On the oiler being 45 turned bottom downward such intercepted oil will return through the tube E into the reser-

voir. So, in case any oil should run down on the outside of the tube C, such oil will flow 50 into the cup or cavity d, and thence through the pipe F, thence into the space within the flange e, and thence through the tube E and into the reservoir. The said flange e operates as a fender or guard to prevent the escape of 55 oil from the chamber b through the joint between the caps B and D. With my improved oil-feeder no oil can get on the outer side of the reservoir A, as any oil that may run down the outer surface of the educt C will be caused 60 to pass back into the reservoir.

By having the chambered cap D separate from and screwed, as described, on the educt C, ready access can be had at any time to the chamber b, top of the cap B, and tube E, for 65 cleaning either of any deposits therein.

I claim in the oil-feeder—

1. The combination of the auxiliary chamber b and its tube F with the reservoir A, its cover B, educt C, and tube E, all being arranged substantially as set forth. 70

2. The combination of the auxiliary chamber b and its tube F with the educt C, cover B, flange e, reservoir A, and tube E, all being arranged substantially as set forth. 75

3. The combination of the auxiliary cap D, open at bottom and provided with the tube F, and screwed upon the educt C, with such educt, the cover B, reservoir A, and tube E, arranged substantially as set forth. 80

4. The combination of the chambered cap D, provided with the cup d and tube F, as described, with the educt C, cover B, reservoir A, and tube E, arranged essentially as represented. 85

5. The chambered cap D, provided with the cup d and tube F, and adapted to screw upon the educt C, in combination with the reservoir A and the cap B, having the said educt, the flange e, and tube E, all being substantially as set forth. 90

DAVID SANDS ROBERTS.
